ICE CRUSHER

Henry J. Talge, Kansas City, Mo., and Sheldon M. Rutter,
Chicago, Ill.

Application December 31, 1953, Serial No. 28,299

Term of patent 14 years

(Cl. D89—1)

Fig. 2.

Fig. 1.

Fig. 3.

To all whom it may concern:

Be it known that we, Henry J. Talge and Sheldon M. Rutter, both citizens of the United States, residing at Kansas City, State of Missouri, and Chicago, State of Illinois, respectively, have invented a new, original, and ornamental Design for an Ice Crusher, of which the following is a specification, reference being had to the accompanying drawing, forming part thereof, in which

Fig. 1 is a front elevational view of an ice crusher embodying our new design,

Fig. 2 is a side elevational view of same, and
Fig. 3 is a plan view of same.

We claim:

The ornamental design for an ice crusher as shown and described.
